KEYBOARD FOR ELECTRIC ORGAN OR THE LIKE

Aaron Orenstein and Louis Golling, Northampton, Mass.

Application May 24, 1954, Serial No. 30,617

Term of patent 14 years

(Cl. D56—1)

Fig. 1.

Fig. 2.

To all whom it may concern:

Be it known that we, Aaron Orenstein and Louis Golling, citizens of the United States, residing at Northampton, in the county of Hampshire, and Commonwealth of Massachusetts, have invented a new, original, and ornamental Design for a Keyboard for Electric Organ or the Like, of which the following is a specification, reference being had to the accompanying drawings forming part hereof.

Fig. 1 is a front perspective view of a keyboard for electric organ or the like, showing our new design; and

Fig. 2 is a rear perspective view of the keyboard shown in Fig. 1.

We claim:

The ornamental design for a keyboard for electric organ or the like, as shown.
